UNITED STATES PATENT OFFICE.

FRANK J. McEWAN, OF CHICAGO, ILLINOIS

COMBINATION-HEEL.

1,346,038.

Specification of Letters Patent.

Patented July 6, 1920.

Application filed January 2, 1920. Serial No. 348,720.

To all whom it may concern:

Be it known that I, FRANK J. McEWAN, a citizen of the United States, and a resident of Chicago, in the county of Cook and State of Illinois, have invented a new and useful Improvement in Combination-Heels, of which the following is a full, clear, and exact description.

My invention relates to improvements in combination heels, and it consists in the combinations, constructions, and arrangement herein described and claimed.

An object of my invention is to provide a combination heel which has greater resiliency and durability than a solid rubber heel.

A further object of my invention is to provide a heel of the type described which can be manufactured cheaply, and which 20 may be adapted for application to shoes of varying sizes and styles.

A further object of my invention is to provide a heel which will not slip on a wet surface, will not mark or mar polished floors, and which will not be noiseless in a manner objectionable to many persons.

A further object of my invention is to provide a heel which is inexpensive and which can be readily and firmly attached 50 to a shoe.

Other objects and advantages will appear in the following specification, and the novel features of the invention will be particularly pointed out in the appended claims.

My invention is illustrated in the accompanying drawings, forming part of this application, in which—

Fig. 1 is a sectional view of the device applied to a man's shoe,

Fig. 2 is a bottom plan view of the heel,

Fig. 3 is a face view of the intermediate layer of the same,

Fig. 4 is a face view of the top layer of the heel,

Fig. 5 is a side view partly in section of the device applied to a lady's shoe.

Referring to Fig. 1, I have shown my device attached to a heel portion 10 of a man's shoe. My device consists of a resilient top layer of soft rubber 11, a relatively thin layer of hard rubber 12, and a bottom layer of leather or leather substitute 13. The layer of leather or leather substitute 13 is cemented tightly to the middle layer of hard rubber 12 and is further secured thereto by stitching as indicated at 14. The mid-

dle layer of hard rubber 12 is firmly cemented to the top layer of soft rubber 11 and may be vulcanized thereto. My device is fastened to the heel portion 10 by a plurality of nails 15. The heads of the latter are countersunk to the level of the hard rubber layer in holes 16 provided in the layer of leather 13 for that purpose.

In Fig. 5 my device is shown applied to a lady's shoe. It will be understood that the heel of a lady's shoe, such as shown, ordinarily consists of a wooden portion 20, a leather covering 21, and intermediate plate 22, and a leather lift 23. In applying my device, the component layers consisting of a top layer of resilient soft rubber 24, a relatively thin middle layer of hard rubber 25, and a bottom layer of leather or leather substitute 26 would be arranged and fastened together in the manner described. The device is then nailed or screwed to the wooden heel portion 20 and is covered by the leather covering 21 which also covers the wooden portion 20. The metal plate 22 and the bottom layer of leather 26 are then attached in any ordinary manner.

It will be understood further that my device may be adapted to all sizes and styles of men's, children's and ladies' shoes.

From the foregoing description of the various parts of the device, the operation thereof may be readily understood. My device has advantages over the ordinary solid rubber heel in that it will frictionally grip a wet surface firmly, will not mark or mar a polished floor, and is not noiseless in a manner that is objectionable to many persons. Articles of clothing, such as trousers may be drawn over the shoe more readily when my device is used than is the case when a solid rubber heel is used, since the garment will stick to the latter. One of the main advantages of my device is in the comfort secured by the use thereof. When a solid rubber heel is used, it must necessarily be of relatively hard rubber to be at all durable. The arrangement of component layers in my device permits the use of a very resilient top layer of soft rubber and greater elasticity which makes for comfort is therefore secured. Furthermore, since the leather layer in my device comes into contact with the ground, the force of the impact is distributed equally over the entire surface of the top layer of soft rubber and the jar that would otherwise result is ab-

sorbed by the same. My device is more durable than the ordinary solid rubber heel for obvious reasons, since the rubber layer does not come into actual contact with the ground.

I claim.

1. A combination heel comprising a wear resisting bottom portion, said bottom portion being formed with a plurality of openings arranged to extend transversely therethrough, a layer of hard rubber disposed above and secured to said wear resisting bottom portion, a layer of soft resilient rubber surmounting said layer of hard rubber and secured thereto, and a plurality of tacks for securing said combination heel to a shoe or similar article, each of said tacks being inserted through one of said openings until the head thereof is substantially flush with the under surface of said layer of hard rubber.
2. A combination heel comprising a wear resisting bottom portion, said bottom portion being formed with a plurality of openings arranged to extend transversely therethrough, a layer of hard rubber disposed above said bottom portion and secured

thereto by stitching, a layer of soft resilient rubber surmounting said layer of hard rubber and secured thereto, and a plurality of tacks for securing said combination heel to a shoe or similar article, each of said tacks being inserted through one of said openings until the head thereof is substantially flush with the under surface of said layer of hard rubber.

3. A combination heel comprising a wear resisting bottom portion, said bottom portion being formed with a plurality of openings arranged to extend transversely therethrough, a layer of hard rubber disposed above said bottom portion and secured thereto by stitching and cementing, a layer of soft resilient rubber surmounting the layer of hard rubber and secured to the latter by cementing, and a plurality of tacks for securing said combination heel to a shoe or similar article, each of said tacks being inserted through one of said openings until the head thereof is substantially flush with the under surface of said layer of hard rubber.

FRANK J. McEWAN.
